METALLIC ROENTGEN TUBE WITH REVOLVING ANTICATHODE

Sergei Sergeeff, Moscow, Union of Socialist Soviet Republics

Application December 6, 1934, Serial No. 756,813.
In Union of Socialist Soviet Republics June 25, 1933

5 Claims. (Cl. 250—35)

There are known powerful (up to 200 ma.) metallic Roentgen tubes for microstructural analysis which work in connection with a four-stage diffusion pump and permit a rapid change of the 5 anticathode (as, for example, the tube by Mr. G. N. Selmayr with a four-stage diffusion pump by Gaede, see the Scientific Journal of Physics, 1924, page 598).

A further increasing of the tube capacity is 10 limited by the degree of heating of the anticathode, said heating being too high in spite of an intensive cooling.

It has been also proposed to overcome this difficulty by employing a revolving anticathode, in 15 the first time in X-ray tubes for surgical diagnosis. No prolonged exposure being required in such cases, these tubes had a revolving anticathode which was cooled owing to the thermal conductivity of the metal without the use of cooling 20 water.

A thoroughly designed construction of a tube with revolving anticathode has been proposed by Bowers, who determined the necessary number of revolutions of the anticathode, the latter being 25 rotated by a magnetic field produced externally of the tube.

This tube is adapted to operate at 650—500 ma. at 40—50 kv. during 0.05 second and at 500—400 ma. during 0.2 second.

30 But such a short duration of exposure is not sufficient for microstructural analysis.

If the exposure lasts several minutes, a continuous water cooling is needed even in the case of a revolving anticathode.

35 The rotation of a water cooled anticathode in X-ray tubes of this kind requires the use of various stuffing boxes which makes very difficult the obtaining of the necessary vacuum within the tube.

40 In a contrary way the present invention permits the arrangement within a high vacuum X-ray tube of a revolving water cooled anticathode without the use of any packing means or any rotary tight sleeves in the high vacuum zone.

45 The invention consists therein that the rod of the anticathode passes through the four-stage diffusion pump which constitutes an integral part with the Roentgen tube.

The rod passes through the pump in such a 50 manner that the space between these parts constitutes a diffusion diaphragm through which the air is exhausted by mercury vapours or the like flowing with great velocity out of an annular nozzle as in usual diffusion pumps.

55 As the rod passes through the second, third

and fourth stages of the pump, the interstices between the rod and the washers separating the stages are overlapped by mercury stoppers.

Such a manner of obtaining tightness is possible owing to the small pressure difference existing between consecutive pump stages and because beginning with the second stage the pressure in the stages is smaller than the mercury vapour pressure at ordinary temperatures.

Thus the tightening by means of stuffing boxes 10 is removed to the zone of preliminary vacuum (low vacuum), where in the four-stage pump the vacuum need not be higher than 15—20 mm. of the mercury column.

The accompanying drawing illustrates, by way 15 of example, two forms of embodiment of the arrangement according to the invention; in both cases the four-stage diffusion pump is of Gaede's system.

The shell 1 of the Roentgen tube is a hollow 20 cylindrical body with passages 2 for the cooling water. A window 3 made of aluminium foil is provided in the shell and serves for letting out the X-rays. On the upper part of the shell 1 is mounted a glass tube 4 which is welded to 25 chromium steel sockets 6—7. The glass tube 4 serves for insulating the cathode 5.

To provide for a prolonged operation of the tube at a large load the water cooling of the cathode can be effected through the nipples 8 and 9. 30 The incandescent cathode is formed as a tungsten coil. For still greater loads the cathode may be of the indirect heating type.

The detachable junction between the shell 1 and the diffusion pump underneath it is effected 35 by a gas-tight glass sleeve 10, hermetically drawn upon a metallic cone which is connected to the shell 1 by means of elastic member 11. The so formed glass receptacle 12 is filled with liquid air for freezing out the mercury vapours.

The revolving anticathode comprises the flat piece 13 firmly fastened to the through tubular rod 14.

In the inner cavity of the anticathode is fixed 45 the funnel-shaped end of a stationary tube 16, through the lower end 17 of which is introduced the cooling water. This water flows out through the annular space between the tube 16 and the inner wall of the tubular rod 14.

The rod 14 of the revolving anticathode 13 is 50 rotated from without by means of the toothed gearing 18.

It revolves in two bearings: the upper bearing 19 operating without lubrication is situated in the high vacuum zone, and the lower bearing 20 55

which is formed as a stuffing box is located in the point where the rod 14 passes from the preliminary vacuum (low vacuum) into the atmosphere.

The revolving rod 14 of the anticathode enters into the diffusion pump 21 through the annular gap of the part 22 which forms the diffusion diaphragm, through which the air is sucked out of the tube by means of the mercury vapours flowing out through the annular nozzle surrounding the part 22.

The four stages of the mercury pump 21 are separated from one another by the discs 23 provided with mercury stoppers 24.

Such a packing is possible in this case only because of the fact that the pressure differences between each two consecutive stages of the pump are very small and because beginning with the second stage the pressure in each stage is smaller than the pressure of mercury vapours at ordinary temperature.

The vacuum pump is connected to the connecting tube 25.

The mercury vapours ascend from the boiling vessel 26 and pass through the nozzles 27 which are arranged in parallel, and through the annular nozzle on the part 22. The condensed mercury flows down through the mercury stoppers 24 and the tube 28, returning back to the boiling vessel 26. Thus the stuffing box is located in the zone of preliminary vacuum, where in the case of a four-stage pump the pressure of 15-20 mm. of the mercury column is sufficient.

Fig. 2 shows another form of embodiment of the object of the invention. In this case the stuffing box referred to above may be eliminated, if the water has a free escape and if there is sufficient pressure in the water supply pipe. Here instead of the stuffing box 20 a water jet pump 29 is formed which creates a vacuum equal to 15-20 mm. of the mercury column.

Such a vacuum makes sure the operation of the four-stage diffusion pump.

If a water jet pump is to be used for producing a pressure drop where the anode rod passes from the preliminary vacuum zone into the atmosphere, the arrangement is such that the water flowing out of the anode rod, as indicated by arrows in Fig. 1, draws the air from the preliminary vacuum through the air space between the anode tube and the tubular casing. The anode rod is

mounted in the preliminary vacuum zone in a ball bearing similarly to the arrangement in the high vacuum zone. Since in the case of a considerable pressure drop for a water jet pump, the velocity of pumping out is much too small, there is provided in the present constructional form a pipe 28 which is connected to a vacuum pump.

What I claim is:

1. In combination, a Roentgen tube including a rotary water cooled anticathode and a carrying rod for said anticathode, a multi-stage diffusion pump connected with said tube and having high and low vacuum zones, said rod extending through said pump and externally thereof through the low vacuum zone, a bearing for said rod in the high vacuum zone of the pump, a second bearing for said rod in the low vacuum zone and a stuffing box at the point where said rod passes from the low vacuum zone into the atmosphere.

2. In combination, a Roentgen tube including a rotary water cooled anticathode and a carrying rod for said anticathode, a multi-stage diffusion pump connected with said tube and having high and low vacuum zones, said rod extending through said pump and externally thereof through the low vacuum zone, a bearing for said rod in the high vacuum zone of the pump, a bearing for said rod in the low vacuum zone and a water jet pump at a point where the rod extends through the multi-stage diffusion pump for creating a vacuum for the operation of the multi-stage diffusion pump and corresponding to 15-20 mm. of the mercury column.

3. An arrangement as claimed in claim 1, characterized in that said multi-stage diffusion pump includes a diffusion diaphragm surrounding said carrying rod.

4. An arrangement as claimed in claim 1, characterized in that said multi-stage diffusion pump includes a diffusion diaphragm surrounding said carrying rod in the high vacuum zone of said diffusion pump.

5. An arrangement as claimed in claim 1, characterized in that said multi-stage diffusion pump includes a diffusion diaphragm surrounding said carrying rod in the high vacuum zone of said diffusion pump, and means for supplying mercury vapors to exhaust the air from said tube.

SERGEI SERGEEFF.
